US0D1070933S

(12) **United States Design Patent** (10) Patent No.: **US D1,070,933 S**
Suchman et al. (45) Date of Patent: ** Apr. 15, 2025

(54) **DEBRIS CONTAINER**(71) Applicant: **iRobot Corporation**, Bedford, MA (US)(72) Inventors: **Jason Jeffrey Suchman**, Arlington, MA (US); **Douglas Dell'Accio**, Boston, MA (US); **Andrew Vincent Wolff**, Norfolk, MA (US); **Flavia Pastore**, Wakefield, MA (US)(73) Assignee: **iRobot Corporation**, Bedford, MA (US)(**) Term: **15 Years**(21) Appl. No.: **29/865,685**(22) Filed: **Aug. 8, 2022****Related U.S. Application Data**

(63) Continuation of application No. 29/811,496, filed on Oct. 14, 2021, now Pat. No. 960,211, which is a continuation of application No. 29/741,453, filed on Jul. 13, 2020, now Pat. No. Des. 934,314, which is a continuation of application No. 29/646,577, filed on May 4, 2018, now Pat. No. Des. 890,231.

(51) **LOC (15) Cl. 15-09**(52) **U.S. Cl.**USPC ..... **D15/122; D32/31**(58) **Field of Classification Search**

USPC D15/122, 132, 138, 199; D32/15-25, D32/30-34, 35

CPC A01G 20/43; B08B 15/002; E01H 1/0836

(57) **CLAIM**

The ornamental design for a debris container substantially as shown and described.

DESCRIPTION

FIG. 1 is a perspective view of the debris container.

FIG. 2 is a front view thereof.

FIG. 3 is a back view thereof.

FIG. 4 is right side view thereof.

FIG. 5 is left side view thereof.

FIG. 6 is top view thereof; and,

FIG. 7 is bottom view thereof.

The broken lines illustrate portions of the debris container that form no part of the claimed design.

1 Claim, 7 Drawing Sheets
